UNITED STATES PATENT OFFICE

EDWARD A. CALAHAN, OF BROOKLYN, NEW YORK.

IMPROVEMENT IN PRINTING-TELEGRAPHS.

Specification forming part of Letters Patent No. 99,401, dated February 1, 1870.

To all whom it may concern:

Be it known that I, EDWARD A. CALAHAN, of Brooklyn, in the county of Kings and State of New York, have invented and made a new and useful Improvement in Printing-Telegraphs; and I do hereby declare the following to be a full, clear, and exact description of the said invention, reference being had to the annexed drawing, making part of this specification, wherein—

Figure 1 is an exterior elevation of my apparatus. Fig. 2 is a view of the interior parts, the front plate being removed. Fig. 3 is a plan of the instrument, and Fig. 4 is a detached plan of the regulating-fly and clock-work.

Similar marks of reference denote the same parts.

In my improved printing-telegraph the type-wheel is revolved by a weight, as permitted by the action of an escapement controlled by electrical pulsations and a magnet. The movement of the type-wheel causes a circuit to remain closed, or nearly so, upon a second magnet, and when the type-wheel is stopped the said circuit is broken, and a fly-clock-motion and connected mechanism makes and breaks gradually a third circuit that operates a magnet that gives the impression.

My instrument is especially adapted to banking and commercial purposes and private telegraphing, because the printing is self-operating during the pause between the transmission of one letter and the next.

I employ a dial circuit breaker and closer as a convenient and reliable mode of giving pulsations to move the type-wheel to the desired point. Several instruments can be placed in the same circuit, and operated simultaneously. The derangement of one instrument has no effect on the others.

One of the special features of my invention relates to the moving of a spring or weight by the action of an armature and lever, and the employment of a train of wheels and a fly, to regulate the gradual movement of the parts in the opposite direction while operated upon by the spring or weight. A pawl is employed, acting upon a disk with a roughened or finely-serrated edge, to allow the movement of the armature and lever without turning the fly back. A disk and pawl of the same char-

acter are employed to move the feed-rollers that draw along the paper. These are to be distinguished from a ratchet-wheel in which a definite movement has to be given, or else the pawl misses a tooth, and the feed fails. This heretofore has been a fruitful source of trouble in printing-telegraphs. In my apparatus it is almost impossible for the parts to become inoperative; but the paper is moved whether the full stroke is given to the armature or not.

In the drawing, *aa* are side plates carrying the parts. *bb* are movable end plates, and a top plate may also be employed to keep dust and dirt out of the mechanism. *e* is a barrel, with a cord, *1*, to a suitable weight. This barrel is fitted so that it may be wound up, if run down, as usual. *c¹ c² c³* is a train of gearing to move the escapement-wheel *d* when the pallets *e* are operated by the armature *e¹* and magnet *f*. *26* is the binding-screw for the line-wire that leads to this magnet *f*, and the return-circuit is through the frame *a* and binding-screw *3*. It is to be understood that the pulsations of electricity are to be sent through this magnet *f* by a finger-key, revolving pointer, or any other device to allow the type-wheel *g* (that is on the shaft *d'*) to be turned around until the proper letter or character is in position for being impressed upon the strip of paper *4*, that is led through the guide *5* below the guide *6*, and over the impression-block *7* to the feeding-rollers *k k'*, hereafter described. *g'* is the inking-roller for the type-wheel *g*, and *8* is a spring to the lever *e²* of the pallets *e*, adjusted to the shaft and thumb-head *9*. The shaft *d'* has a ratchet-wheel, *l*, that acts to press back a tooth, *10*, and move the lever *l'* away from said ratchet-wheel while the said ratchet-wheel is revolving; but when it and the type-wheel stop the tooth *10* falls into the opening between the ratchet-teeth. The lever *l'* has an arm, *11*, going through the plate *a* freely, and a spring, *12*, tends to draw the lever *l'* toward the wheel *l*. This movement, however, would be sudden when the wheel *l* stopped were it not for the fly *m*, acted upon by the train of gearing *m'*, so as to have the necessary speed communicated to said fly through the agency of the lever *l'* and spring *12*, said lever *l'* being provided with a link, *13*, to a swinging plate, *14*, on which is a spring-pawl, *15*, taking the roughened edge of the

disk 16. Hence, as the lever l' is pressed back by the tooth 10 and ratchet-wheel l , the pawl 15 takes a fresh position against the edge of the disk 16, and when the ratchet l permits thereof the movement of the lever l' is gradual at any speed to which the parts may be adjusted. This movement of the lever l' I employ to close and break automatically the circuit to the second magnet n . This is effected by the spring 18 taking the screw 19, and closing the circuit from the binding screw 20 through the magnet n , insulated arm 21, screw 19, spring 18, lever l' , frame a , and binding-screw 3.

While the current passes through n the armature n^1 is attracted, and the breaking of the circuit through n allows the armature-lever n^2 to move gradually, as next described, to close the circuit that effects the printing, and this, it will be seen, occurs when the type-wheel stops.

The lever n^2 is connected by a link, 22, with a swinging plate, p , that moves upon the shaft 23 of the roughened edged disk r , and carries a spring-pawl, s , which takes against the edge of the disk r ; and 24 is a spring, adjustable by the shaft and turning-head 50, to move the plate p more or less rapidly when the armature n^1 is released.

The movement of the armature n^1 , lever n^2 , and parts connected therewith, is rendered gradual by the train of wheels r' , that multiply speed to the fly s' , the resistance of which upon the atmosphere regulates the speed of movement.

t is a small frame, that is insulated from the main frame a , as is also the connection t' that passes through said frame a to the magnet u that effects the printing. Said magnet u is in a circuit connected with the binding-screw 2, the other pole of the battery being connected to the frame a and binding-screw 3.

The arrangement of the batteries and line-connections, being of any desired character, need not be detailed.

On the axis of the armature n is a lever, n^3 , having two studs, 28 29, projecting through openings in the frame a , and upon the frame t is a swinging circuit-breaker, v , having three arms, the arm 30 coming near an adjusting-screw, 31, through the stud 29, the other arm, 32, acting as a counterpoise, and the arm 33 having a double inclined end acting with the spring 34, and its inclined end, to insure the movement of v fully in either direction.

An arm, 35, extends from the stud 28, and acts, by a screw, upon an insulating-block upon the arm 33.

When the armature n^1 is attached, the parts stand in the position illustrated in the separate view Fig. 5, the screw 31 being out of contact with the arm 30; hence, the circuit through u is broken at this point. As soon as the armature n^1 is released, and begins to move, the screw 31 takes the arm 30, closing the circuit through the magnet u , and giving the impression through the armature u^1 , lever

u^2 , and pressure-pad 7, that is carried by the said armature, the paper 4, pad 7, and guide 6, all being moved with the armature u^1 and lever u^2 .

The contact of 31 with 30, and the pressure from the spring 24, is sufficient to move the circuit-closer v , notwithstanding the inclined end of the arm 33, and the spring 34, and the incline of the arm 33, passes beyond the incline of the spring 34; hence, the arm 30 is suddenly drawn away from 31 by the action of the spring 34 breaking the circuit of u , and the parts assume a normal position, as seen in Fig. 1, until the type-wheel is moved again to set the next letter or character.

It will now be understood that this apparatus is easily adjusted to the speed with which the operator manipulates; if he is rapid, the spring 24 will require to be under more tension by turning the shaft and button 50 so that the fly s' will move more rapidly, and bring the impression-magnet into operation almost instantly; if the operator is slow, or hesitates in his movements, the spring 24 must be under a light tension, to prevent a false letter being imprinted.

I here remark that the type-wheel for general purposes should contain letters and figures; it may also contain fractions, and there being a blank space on the type-wheel, the space between the words will be produced at that point.

I provide a means for setting the type-wheel, should it miss a movement; this consists in an arm, w , that is upon a rod, 38, that is pushed in and takes a pin, 39, on the wheel d , and prevents the wheel d and type-wheel turning any further, even though the armature e^1 may be vibrated in setting other instruments in the same line to the determined starting-point.

The device for moving the rollers k k' in feeding the paper consists in a spring, 41, that is attached at the end to the armature-lever u^2 , and said lever is provided with a connection to the swinging plate 42, upon which is a spring-pawl, 43, taking the roughened surface of the disk x on the shaft of the roller k , and 44 is a holding-pawl to the disk x ; hence, as the impression is given, the pawl 43 is drawn back over the surface of the disk x , and, as the armature and lever are returned to position by the spring 41, the pawl 43 revolves the disk x and feed-roller k , and moves the paper.

The cam 51 becomes a stop to the movement of the lever u^2 , and thereby the extent of motion given to the feed-rollers can be regulated.

The feed-roller k is formed with an edge of fine teeth, and should be double, to act each side of the impression on the paper. The roller k' should also be double, and kept toward k by spring 46, so as to gripe the paper.

I am aware that electro-magnets have been employed to act upon armatures, stops, and breaks, that control the movement of clock-work actuated by springs or weights, but

these devices require winding up to furnish the actuating-power. In my device the magnet furnishes the actuating-power.

What I claim, and desire to secure by Letters Patent, is—

1. A train of gearing and a fly applied, substantially as specified, to render gradual a motion derived from the movement of the armature of an electro-magnet, substantially as specified.

2. The combination of the following devices: An electro-magnet and armature, a fly and train of gearing, a disk and pawl, and an actuating spring or weight, the parts being constructed and arranged so that the actuating spring or weight is moved by the armature, and gives motion to the regulating-fly, substantially as set forth.

3. The spring 24, in combination with the train of gearing, fly, armature, and adjusting-device 50, whereby the speed of movement is regulated by the adjustment of the spring 24, substantially as set forth.

4. The arrangement of three electro-magnets, and their connections, substantially as specified, so that the first shall regulate the movement of the type-wheel, and direct an electrical current through the second magnet; the third magnet is brought automatically into action, to give the impression, when the circuit through the second magnet is broken

by the stopping of the type-wheel, substantially as set forth.

5. The lever l' , arm 11, and yielding circuit-closer 18, in combination with the armature e^1 , to close and break the circuit to the magnet n , as set forth.

6. The ratchet-wheel l , dog 10, and lever l' , in combination with the pawl s , disk r , fly s' , and circuit-breaker v , substantially as set forth.

7. The lever v , with the arms 30 and 33, in combination with the armature n^1 , lever n^3 , arm 35, and inclines 34, and circuit-closer 31, substantially as set forth.

8. A swinging arm, 30, yielding incline 34, in combination with a circuit-closer having a limited movement, substantially as specified, so that the circuit is broken at the end of the movement by the action of the incline.

9. The means herein specified for giving motion to the feed-wheel of a printing-telegraph, the same consisting in a pawl and plate, swung by the armature-lever upon the axis of the feed-wheel, in combination with a disk having a roughened periphery, substantially as set forth.

In witness whereof I have hereunto set my signature, this 8th day of September, A.D. 1869.
